WINDER E. GOLDSBOROUGH, OF SOUTH NORWALK, CONNECTICUT, ASSIGNOR TO
DOHERTY RESEARCH COMPANY, OF NEW YORK, N. Y., A CORPORATION OF DELA-
WARE

CONVEX CYLINDER AND PISTON HEAD

Application filed July 30, 1929. Serial No. 382,140.

This invention relates to cylinder and piston construction suitable for use in connection with internal combustion engines, compressors or similar mechanisms having a piston reciprocating in a cylinder.

It is the principal object of this invention to provide a construction of the cylinder head together with a complementary construction of the piston which shall provide for a maximum strength of these parts for a given quantity of metal used in their construction.

It is a further object of this invention to provide a construction which when used in connection with compressors and especially isothermal compressors will give a large area of cylinder wall by which the heat of the gases being compressed may be absorbed while at the same time affording such strength and rigidity of structure as to permit extremely high compression pressures.

It is a further object of this invention to provide a construction which when designed for use as an internal combustion engine affords a means whereby the fuel injected therein is completely diffused through the combustion supporting medium in the engine cylinder.

To this end, it is a feature of the invention to provide a means whereby the maximum of turbulence is obtained during the entrance into the system of the combustion supporting medium combined with the high penetration and diffusion of the fuel supply injected therein.

It is a further object of this invention to provide a construction which, when designed for use in internal combustion engines of the type in which the combustion supporting air charge is supplied to the working cylinder when the piston of the same is at or near upper dead center position, affords a means whereby the incoming air is rapidly heated to a high temperature by radiant energy received from the surrounding surfaces of the combustion chamber, and affords means whereby the exposure to such radiant surfaces is greater than is possible in conventional constructions.

To this end it is a feature of the invention to coat the inwardly projecting surfaces of

the cylinder head and the co-acting surfaces of the piston with a refractory material capable of withstanding high temperatures and adapted to heat the incoming air charge not only by contact between the gases and the highly heated surface, but also by means of radiation directly into the body of air itself.

These and other objects of the invention will further appear in connection with the following detailed description.

The accompanying drawing represents a longitudinal section taken through the cylinder head and piston of an internal combustion engine constructed in accordance with this invention.

Referring to the drawing, reference numeral 10 indicates the cylinder of an internal combustion engine having a head 12 of conical or concavoconvex construction. The head 12 projects downwardly into the cylinder and bears at or near its apex a fuel nozzle 14. A piston 16 is reciprocative in the cylinder 12. The piston 16 has a conical or concavoconvex head 18 which head is of such construction as to closely correspond to the conical head 12 of the cylinder, the two being so arranged that the clearance space 20 formed therebetween when the piston 16 is in its upper dead center position is a thin chamber of funnel shaped construction. A passage 22 is provided in the piston 16 and opens into the space 20 at the apex of the conical portion 18 of the piston. The passage 22 is adapted to register with the passage 24 in the sidewall of the cylinder 10 when the piston 16 is in or near its upper dead center position. A second passage 26 is provided in the sidewall of the cylinder 10 and is adapted to be uncovered by the piston 16 after the same has moved downwardly upon its working stroke.

In operation, when the parts are in the position shown in Fig. 1, with the piston moving upwardly, the passages 22 and 24 begin to register, and a charge of compressed air from a reservoir or compressor attached to passage 24 passes upwardly through the piston passage 22. As the same enters the clearance space of the engine, it is given a whirling motion by the deflecting vanes 28.

At this point fuel is supplied through the injection nozzle 14 and because it does not need to traverse a comparatively large space before contacting with the wall of the piston

- 5 16 which is immediately opposite, it may be so highly atomized by the usual mechanical means, that is to say, atomized to such a degree of fineness, that the various particles composing the fog or spray of liquid fuel in
- 10 the space 20 possesses too little penetrative power to be projected very far through the air under high pressure in this space. The air of combustion, however, entering through the passage 22 carries the highly atomized
- 15 fuel away from the fuel nozzle 14 and burns therewith while moving into the outer portions of the clearance space 20.

When the invention is applied to an internal combustion engine as is illustrated in this figure, it is preferable to reduce the radiation loss which would otherwise be greater than in conventional construction, by the use of refractory material indicated at 29 upon all surfaces which come in contact with the

25 highly heated air or products of combustion.

The specific engine herein shown is of the type in which combustion supporting air from an external source is supplied when the working piston is at or near its upper dead center position. The invention is particularly useful in connection with such engines since any heat absorbed by the incoming gases from the walls of the cylinder increases their heat content at a point in the

30 cycle at which such heat may be converted into useful work. Only by providing refractory capable of withstanding these temperatures can the engine utilize this desirable feature. The conical surface in conjunction

35 with the refractory material permits of a large measure of such heating in the short time available during the upper portion of the working stroke.

The described construction provides an

40 engine in which the distance at which the fuel is required to penetrate solely by the velocity given to it by its injection into the combustion spaces are greatly reduced. At the same time the concavoconvex form of

45 the cylinder head and of the piston head gives a more rigid construction to these parts, and they are able to withstand far higher pressures than were they of flat construction.

Although there has been herein described

50 but a single specific embodiment of the invention, it will be obvious to those skilled in the art that various modifications may be made in design and construction without departing from the principles herein set forth.

55 Having thus described the invention, what is claimed as new is:

1. In an internal combustion engine having a cylinder and a piston reciprocative therein, the head of said cylinder being of

60 conical construction and projecting into said

cylinder, with a fuel nozzle at the apex of said conical cylinder head, and means to supply combustion supporting air through the piston at a point adjacent said nozzle.

2. In an internal combustion engine having a cylinder and a piston reciprocative therein, the head of said cylinder being of conical construction and projecting into said cylinder, with a fuel nozzle at the apex of said conical cylinder head, means to supply combustion supporting air through the piston at a point adjacent said nozzle, and means to give said air a rotating motion.

3. In an internal combustion engine, a cylinder, a piston reciprocative therein, the head of said cylinder being of conical construction, a nozzle at the apex of said conical head, and means to supply combustion supporting air adjacent said nozzle at the time said piston is in about its upper dead center position.

4. In an engine having a cylinder and a piston reciprocative therein, the head of said cylinder being of conical construction and projecting into said piston, means to supply combustion supporting air through said piston, and means to give said air a rotating motion.

5. In an engine having a cylinder and a piston reciprocative therein, the head of said piston being of conical construction and projecting into said piston, a passage to supply combustion supporting air through said piston, and a refractory coating on the surfaces of said piston head and said passage.

6. In an internal combustion engine having a cylinder and a piston reciprocative therein, a head of conical construction for said cylinder, said head projecting in said cylinder, the internal surfaces of said head being lined with heat refractory material.

7. In an internal combustion engine having a cylinder and a piston reciprocative therein, a head of conical construction for said cylinder, said head projecting in said cylinder, said piston having a head of conical construction adapted to co-act with the head of said cylinder to form therewith a funnel shaped combustion space, the surfaces forming the combustion space being covered with heat-refractory material, and means to supply air to said combustion space when the piston is in about its upper dead center position.

8. In an internal combustion engine having a cylinder and a piston reciprocative therein a head of conical construction for said cylinder, said piston having a head adapted to coact with the said cylinder head to form therewith a funnel shaped combustion space, the said piston head being lined with heat-refractory material.

In testimony whereof I affix my signature.

WINDER E. GOLDSBOROUGH.
